BRIDGING PLUG

Wendell B. Steward, Houston, Tex., assignor to
 Schlumberger Well Surveying Corporation,
 Houston, Tex., a corporation of Delaware

Application December 10, 1942, Serial No. 468,461

17 Claims. (Cl. 166—13)

This invention relates to bridging plugs for bore holes. More particularly it relates to bridging plugs and setting tools therefor that can be run into the hole in connection with an electric cable, the setting operations being controlled from the surface.

The present invention contemplates providing both permanent and retrievable plugs adapted to be set by a novel motor operated setting tool which provides an extremely high force for setting the packer of the plug. The bridging plug and setting tool are lowered into the bore hole on an electric cable which not only supports the weight of the apparatus but also enables the motor in the setting tool to be energized from a source of electrical energy located at the surface. This permits complete surface control of the apparatus and enables an indication of the functioning of the bore hole equipment to be obtained.

Accordingly, it is an object of this invention to provide a new and improved apparatus employing an electric cable for positioning a bridging plug in a bore hole.

It is also an object of this invention to provide a bridging plug which is capable of being readily drilled through when it is no longer needed.

Another object of this invention is to provide a bridging plug in which the packer can be very tightly expanded into engagement with the casing.

Another object of this invention is to provide a bridging plug which may be retrieved from the bore hole after it has served its purpose.

A further object of the invention is to provide a setting tool which is released from the bridging plug when a predetermined setting force has been obtained.

Another object of this invention is to provide a setting tool which provides a known force to set a bridging plug in a bore hole.

Still another object of this invention is to provide plug setting apparatus including means whereby the force applied in setting a bridging plug in a bore hole is continuously indicated at the surface.

An object of this invention is to provide a setting tool of the above character which may be released from the bridging plug by the operator at any time, whereby the operator can set the plug to any desired degree and then release the setting tool.

A further object of the invention is to provide a bridging plug and a setting tool therefor which cannot be prematurely set and whose operation

is independent of the ambient hydrostatic pressure in the bore hole.

A further object of this invention is to provide a new and improved tool for setting a bridging plug in a bore hole, which tool can be completely controlled from the surface.

A still further object of this invention is to provide a setting tool which supplies a controlled, uniform increase in pressure to a packer, insuring good alignment of the parts and a perfect seal between the packer and the wall of the bore to be packed off.

Further objects and novel features will become apparent from the following detailed discussion 15 of the accompanying drawings, in which:

Figure 1 is a partial view in longitudinal section through a bore hole showing a setting tool and bridging plug constructed according to the invention in position before the plug is set;

Figure 2 is a view in longitudinal section through a setting tool and retrievable type of bridging plug constructed in accordance with the invention;

Figure 2a is an enlarged view in longitudinal 25 section of the plug shown in Figure 2;

Figure 2b is a cross-sectional view taken along line 2b—2b of Figure 2a and looking in the direction of the arrows;

Figure 2c is an enlarged view in longitudinal 30 section of the upper portion of the plug and the lower portion of the setting tool of Figure 2b showing the manner in which the setting tool is released from the plug;

Figure 2d is a perspective view of the clutch 35 element shown in Figure 2b, divided diametrically to show the grooves therein.

Figure 3 is a schematic wiring diagram illustrating the equipment and control apparatus therefor utilizing a single conductor cable;

Figure 4 is a view in longitudinal section 40 through a permanent type of bridging plug;

Figure 5 is a view in longitudinal section through a modified permanent type of bridging plug;

Figure 6 is a schematic wiring diagram illustrating a modified circuit employing a three conductor cable; and

Figure 7 illustrates a further modification of the invention.

Figure 1 illustrates the arrangement of parts in a typical assembly and comprises a bridging plug 10 attached to a setting tool 11 above which may be positioned a jarring assembly 12, all of which are lowered into a cased bore hole 13 by an electric cable 14, which is manipulated by

a winch 15 at the surface. The jarring assembly 12 is sometimes used when loosening a retrievable type of bridging plug. It may be of any conventional type and forms no part of the present invention. The action of the jarring assembly 12 is simply to impart a hammering action after the slips of the plug 10 have been released from the casing, as will be more fully explained in connection with the subsequent figures. A jarring assembly is not normally included in the assembly when the bridging plug 10 is being run into the hole.

In Figure 2 are shown the setting tool 11 and the plug 10 in its initial unexpanded position. The setting tool 11 comprises a tubular housing 20 filled with an incompressible fluid 20', such as oil, for example, within which is mounted an electric motor 21. The motor 21 is of any conventional type but should preferably be capable of developing a high torque. When a single conductor cable is employed to lower the equipment into the bore hole, as shown in Figure 3, the motor 21 is preferably of the series type, which develops a very high starting torque. If a three conductor cable is employed, as shown in Figure 6, the motor 21' is preferably an induction motor.

A reduction gear box 22 is operatively connected to the shaft of motor 21, serving to reduce its speed of rotation and increase the torque developed thereby. The gear ratios in the box 22 will, of course, depend upon the speed of the motor 21 and the desired output speed, but the reduction ratio will preferably be quite high, 100 to 1 or more, permitting a very high torque to be available from a relatively small motor. A Sylphon bellows 23, communicating with the bore hole fluid L through a passageway 24 formed at any convenient location in the housing 20 serves to maintain pressure equilibrium between the bore hole fluid L and the fluid 20' in the housing 20. Conventional guide springs 25 are attached to the periphery of the housing 20 and serve to prevent it from rotating during the setting or retrieving of the bridging plug 10.

The output shaft 22' of the gear box 22 is connected to a member 26, which passes through a partition 27 in the housing 20 and through a packing gland 28 and a packing nut 29. The packing gland 28 and packing nut 29 may be of the low pressure variety, as there will normally be very little pressure difference between the inside and the outside of the housing 20, due to the presence of the Sylphon bellows 23. Obviously, the Sylphon bellows 23 could be eliminated by providing a high pressure type packing instead of packing gland 28; but as high pressure packings produce a very high friction against the rotating member 26, the arrangement shown in Figure 2 is preferred.

At the lower end of the member 26 is formed an enlarged portion 30 having an axially threaded bore 31 therein within which is adapted to be received a threaded rod 32 secured to the bridging plug 10 below. The lower end of the bore 31 is funnel-shaped as at 33 (Fig. 2a) to facilitate the entrance of the rod 32 into the bore 31. Two pins 34 urged downwardly by springs 35 are positioned in longitudinal bores 35' formed in the lower end 30 of the member 26, the upper ends of the springs 35 being secured within the enlarged portion 30 of the member 26. The pins 34 cooperate with arcuate slots 37 having inclined bottoms formed in a laterally extending member or nut 36 (Figures 2b and 2d) which is threaded on the rod

32. The pins 34 and the slots 37 comprise a uni-directional clutch arrangement such that when the member 26 is rotated in one direction, clockwise, for example, the nut 36 is rotated in the same direction; but if the direction of rotation of the member 26 be counter-clockwise, the nut 36 does not rotate. The top end of pins 34 are temporarily secured to springs 35 such as by soldering or frictional engagement. The upper ends of springs 35 are secured to the top of bores 35' in any suitable way to prevent the pins 34 and springs 35 from falling out when the setting tool is removed from the bore hole. This construction permits removal of the entire setting tool, as will be subsequently explained.

A second set of slots 38 is formed on a different radius in the nut 36 and have their bottoms inclined in the opposite direction so that if the pins 34 are removed and the setting tool 11 then provided with pins 34' similar to the pins 34, which cooperate with the inclined slots 38 (Fig. 2d), the direction of rotation imparted to the nut 36 by the member 26 is reversed. The pins 34 and 34' coact with the slots 37 and the slots 38, respectively, but never coact with both sets of slots at the same time. The above described pin and slot arrangement provides a unidirectional clutch, or ratchet, which may be set to act in either direction. The clutch functions to transmit rotation in only one direction during any one trip of the device into the bore hole. If the threads on the support 40 are right-hand threads, the pins 34' coact only with the slots 38, thereby imparting only counter-clockwise direction to the nut 36 to permit contraction of the plug. In like fashion, the pins 34 coact with the slots 37 and impart only clockwise rotation to the nut 36 when the plug is to be expanded in the bore hole.

The bridging plug 10 is of the retrievable type and it comprises a central rod 40 of enlarged diameter (Fig. 2a) integral with the lower end of the threaded rod 32, on which central rod is mounted a flexible packing member 41. For the sake of clarity this central rod 40 will hereinafter be referred to as a packer support, or support. The packing member 41 is adapted to be compressed into engagement with the bore hole casing by retainers 42 and 43 slidably mounted on the support 40 at its upper and lower ends respectively, and which are slidably mounted on opposite ends of the support 40 and are adapted to be forced toward one another in a manner well known in the art by the combined action of conventional slips 44 and 45, keyed, preferably by means of T-shaped keys and key slots, to frusto-conical or tapered expanding members 46 and 47. The upper frusto-conical member 46 is held against rotation relative to the tubular housing 20 by a plurality of guide pins 39, which are threadedly secured to the housing 20 of the setting tool 11 and which have a sliding fit in holes 48 formed in the upper face of the expanding member 46. A ball or roller thrust bearing 49 is inserted between the lower face of disc 36 and the upper face of the member 46 to reduce the friction between them.

A small compression spring 50 is interposed between the lower end of tapered member 46 and a shouldered portion 46' formed in the retainer 42. A similar compression spring 51 is interposed between a shouldered portion 47' formed in the retainer 43 and the tapered member 47. The tapered member 47 includes a frusto-conical sleeve 47a that is supported on and fixed

with relation to a shaft 47b having a laterally extending disc-like stop member 47c on its lower end. The shaft 47b is secured to the lower end of the support 40. The action of the two coil springs 50 and 51 maintains the assembly in its unexpanded position as shown in Figure 2. The natural elasticity of the packer 41 also assists in maintaining the assembly in its unexpanded position when being raised or lowered in the bore hole. Guide pins 52 and 53 may be inserted between the retainers 42 and 43 and the slips 44 and 45, respectively, to prevent all parts of the plug 10 from rotating relative to the housing 20 when the motor 21 of the setting tool 11 is energized. The guide pins 53 and cooperating slots 53' should preferably be T-shaped so that the slips 45 will be maintained against the retainer 43. Any other suitable means may be used for this purpose. Any suitable safety measures may be provided; for example, the rod 32 may be reduced in cross-section as at 32', in order that it may be broken, if necessary, by tension applied through the cable.

A typical electric circuit that can be utilized with a single conductor cable is shown schematically in Figure 3. It comprises essentially a source of direct current 60 connected through an ammeter 61 and a rheostat 62 to the central terminals 63a and 63b of a double-pole, double-throw switch 63. In order to permit reversal of the direction of the current flowing to the bore hole equipment, the terminals 64 and 65 of the switch 63 are connected together and to the single conductor cable 14 going into the bore hole, while the terminals 66 and 67 are connected together and to the metallic sheath of the cable or to a suitable ground.

The lower end of the cable 14 is connected to one of the terminals of the field winding 21f of the motor 21, the other terminal of which is connected to a central terminal 68 on a double-pole, double-throw, relay type switch 70. The lower end of cable 14 is also connected to one terminal of the energizing solenoid 69 of the relay 70, the other terminal of which is connected to the cable sheath or other ground in the bore hole. One terminal of the armature 21a of motor 21 is connected to the terminals 11 and 12 of the relay switch 70, while the other armature terminal is connected to the terminals 73 and 74, as is apparent from Figure 3. The other center terminal 75 of the relay switch 70 is connected to ground. The relay switch 70 is preferably of the polarized type, but it may be of any variety which will accomplish interchanging the armature or the field leads when the direction of the current flow through the cable 14 is reversed.

In operation, the parts are assembled at the surface as shown in Figure 2 and attached to the electric cable in the conventional manner. The winch 15 is rotated and the bridging plug 10 and setting tool assembly 11 lowered to the desired depth in the bore hole. The switch 63 (Figure 3) is closed, thus energizing the motor 21 of the setting tool 11. As the setting tool housing 20 is held from rotation by the guide springs 25, the motor 21, acting through the reduction gear assembly 22 and the member 26, rotates the nut 36 threading it downwardly along the threaded rod 32 of the bridging plug 10. As the nut 36 threads downwardly along the rod 32, the two tapered members 48 and 49 are forced toward one another, moving the slips 44 and 45

into engagement with the casing (not shown). Continued rotation of the motor 21 compresses the flexible packing member 41 longitudinally and forces it into engagement with the casing (not shown). The teeth on slips 44 and 45 are faced such that the two slips 44 and 45 move toward one another relatively easily, but the reverse action is essentially prevented.

As the packer 41 is being expanded into engagement with the casing (not shown), the load upon the motor 21 increases. Hence, it draws an increased amount of power, which is indicated on the ammeter 61 of Figure 3. By suitable calibration of the surface indicating instrument, the progress and stage of the setting operation are continuously indicated.

The motor 21 is maintained energized until the desired setting torque is being supplied to the bridging plug 10, as indicated by the surface instrument 61, or until the motor 21 stalls. The surface switch 63 is then thrown to the opposite position, thereby reversing the direction of rotation of the motor 21. When this condition obtains, the clutch assembly, comprising the pins 34, inclined grooves 37 in the nut 36, slips, unthreading the member 30 from the threaded rod 32 of the bridging plug 10. It should be emphasized that the nut 36 remains in its tightened position, positively preventing release of pressure from the bridging plug 10. After the setting tool 11 has been completely disconnected from the bridging plug 10, the setting tool 11 and supporting cable may be removed from the hole.

After the bridging plug has served its useful purpose, it may be retrieved from the bore hole by removing the clutch pins 34 from the bores 35' and securing the pins 34' within other bores 35'' closer to the center of the enlarged portion 30 on the member 26 (Fig. 2c) and lowering the setting tool 11 into the hole on the electric cable. As the bridging plug 10 is symmetrical and generally rather long in comparison to its diameter, the upwardly extending threaded rod 32 will be very near the axis of the casing. The guide springs 25 on the setting tool 11 also serve to keep it centered in the hole. Consequently, the funnelled portion 33 of the member 30 in the setting tool 11 will pass over the upper end of threaded rod 32 and align the two axially.

The surface switch 63 is then thrown to the position for setting the plug, causing the member 26 to be threaded along rod 32 until the clutch pins 34' enter the inclined grooves 37 in the nut 36. When that occurs, the direction of rotation of the motor 21 is reversed, causing the nut 36 to be threaded upwardly along the threaded rod 32, thereby returning the bridging plug 10 to the position shown in Figure 2.

Due to the extreme biting action between the slips 44 and 45 and the casing, or due to a partial vulcanizing of the packer 41 against the casing, the plug 10 may not be completely released from the casing. In such case, a pull on the supporting cable usually releases the plug 10. If it does not, a jarring member 12 (Figure 1) can be positioned above the setting tool 11 to impart a jarring action to the released plug 10. The compression springs 50 and 51 insure that the bridging plug 10 will contract uniformly and properly when released.

A permanent type plug 10' which is set by the same setting tool 11 is shown in Figure 4. This plug is similar in many respects to the one described in connection with Figure 2, the most notable exception being the direction of the taper

on the two tapered members which expand the slips. In this embodiment, a flexible packing member 41 is positioned about a support 40 between two retainers 42 and 43. A key 85 is formed on the upper reduced portion 40' of support 40, just below the threaded portion 32. The key 85 cooperates with a keyway 87 formed in the upper tapered member 88, preventing relative rotation between the two. The plug 10' is provided with an upwardly and inwardly tapering expanding member 88 and a downwardly and inwardly tapering member 89, which members are adapted to cooperate with similarly tapered slips 88' and 89' to expand the packing member 41 into engagement with the bore hole casing. The slips 88' and 89' may be retained initially in their contracted position as shown by any suitable means, as, for example, by passing small coil springs or pieces of wire 91 and 93 through holes 99 and 100 in the slips 88' and 89', respectively. Above the slips 88' is disposed a laterally extending member or disc 90 through which force may be transmitted from the disc 90 to the slips 88'.

The lower expanding member 88 is slidably supported on the shaft 89a of the laterally extending stop member 89b which is secured to the end of the support 40.

In operation, the permanent plug 10' of Figure 4 is very similar to that described in Figure 2. The action of the setting tool 11 causes the nut 36 to be threaded downwardly along the threaded rod 32, forcing the slips 88' and 89' into engagement with the casing (not shown). Further rotation of the nut 36 forces the two tapered expanding members 88 and 89 toward one another, thereby compressing the packing member 41 and causing it to expand laterally into engagement with the casing. In this embodiment, it will be noted that if either end of the bridging plug 10' is subjected to excessive pressure or other force, the plug 10' will be set tighter in position. Accordingly, a plug is provided which does not tend to slide up or down the casing when force is applied to it after the setting has been completed. Inasmuch as all parts of the plug 10' are designed to have a considerable cross-sectional area, the plug 10' has sufficient strength to enable it to function properly even when made of cast iron or other material that can be easily drilled.

Figure 5 illustrates a modified type of non-retrievable bridging plug 10" in which the packer is partially expanded into engagement with the casing before both sets of slips contact the casing, and also one in which the bridging plug is positively held in retracted position during the descent by shear pins or screws. This form is similar to the embodiment shown in Figure 4 except that the slips 88' are secured to the tapered expanding member 88, by screws or other suitable securing means 94 that can be readily sheared off. In addition, downward movement of the support 40 is prevented by ratchet teeth 95 formed on the upper reduced portion 40" of the support 40, which is adapted to cooperate with a pawl 96 secured within the tapered expanding member 88. The pawl 96 is normally maintained in engagement with the ratchet teeth 95 by means of a conventional leaf spring 98.

In operation, the bridging plug 10" is run into a hole attached to the setting tool 11. The motor of the setting tool is energized, causing the disc 90 to be threaded downwardly along the rod 32. The relative motion between the nut 36 and the rod 32 causes the stop member 89b of the

support 40 and the slips 88' to be raised, causing the slips 88' to bite the casing. Continued rotation of the nut 36 along the threaded rod 32 causes the flexible packing member 41 to be partially expanded, the pawl and ratchet mechanism 96 and 98 locking the assembly in the expanding positions as the setting proceeds. When additional force is applied to the disc 90, and hence to the slips 88', the screws 94 are sheared, permitting the slips 88' to travel easily along the tapered member 88. Continued rotation of the nut 36 forces the upper slips 88' into engagement with the casing and completes the expansion of the packer 41.

It will be noted that at the beginning of the setting operation, the power delivered to the motor 21 will be relatively small, as no great load is imposed upon it. As the lower slips 88' begin to contact the casing and the packer 41 begins to expand, additional work will be required of the motor 21 with a corresponding increase in the reading of the surface instrument 61. When the screws 94 shear, the torque required from the motor will be greatly reduced, with an attendant sudden drop in the energy being sent from the surface. As the setting operation proceeds, the current will again rise to a maximum value when the plug 10" is set. Thus, the various operations of the setting of the plug will easily be discerned by noting the readings of the ammeter 61.

In the event it is desired to use a multi-conductor cable, for example, a three conductor cable, the circuit shown in Figure 6 may be employed. As shown in the figure, electric power is supplied from any suitable three phase supply a, b, c, by means of the conductors 80a, 80b, and 80c, through a switch 80 to a double-pole, double-throw reversing switch 82 at the surface. The function of the switch 82 is to reverse the leads 80a and 80b in the three phase system. Three-phase power is supplied through the leads 80a, 80b, and 80c in the supporting cable (not shown) to a three phase motor 21' in the bore hole. By manipulating the switch 82, the motor 21' may be made to rotate in either direction to perform the functions described above.

Figure 7 illustrates an embodiment of the invention which is designed to provide a known predetermined force for setting the plug. Referring to Figure 7, the housing 20 is provided with a transverse member 101 having a central aperture 102 through which the rod 32 extends. Rotation of the rod 32 with respect to the housing 20 is prevented by a key 103 on the transverse member 101 which cooperates with a keyway 104 on the rod 32, so that the guide springs 26 shown in Figure 2 may be eliminated. Spacers 105 formed integrally with the housing 20 serve to maintain a fixed distance between the member 20 and the frusto-conical or tapered member 46, and a ball or roller thrust bearing 48 is disposed between the member 20 and the transverse member 101.

The lower portion of the rod 32 is provided with a buttress thread 106 and extends through a similarly threaded split nut 107, the parts of which are maintained in a recess 108 in the tapered member 46 by a plurality of spring members 109 secured to the spacers 105. The split nut 107 is preferably made in three or more parts. The rod 32 is also provided with a weakened portion 32' which is designed to break when the force applied to the ends of the packer 41 ex-

ceeds the force required to expand it fully into packing position.

In setting the plug 10", the motor 21 (Fig. 2) is energized and drives the member 30 through the gear box 22. This causes the rod 32 to move upwardly with respect to the housing 20, thereby raising the segments of the split nut 107 against the spring members 109 until they have sufficient room to jump down one thread on the rod 32. The nut 107 and the rod 32 thus form a nut and ratchet mechanism. After the packer 41 has been fully expanded, continued rotation of the member 30 breaks the rod 32 at the weakened portion 32', thus preventing damage to the bore hole casing or the packer material from excess pressure.

It will be noted that even if an undue load is thrust upon the motor 21 by sand or other foreign matter getting into the equipment, force will be applied to the packer 41 until the rod 32 breaks so that the packer 41 will be set properly.

Inasmuch as bridging plugs are generally set in the cased portion of a bore hole, the invention described in the foregoing specification has been illustrated as applied in cased holes. It is to be understood, however, that the equipment is equally applicable to operations conducted in the uncased portion of a hole. It is also within the purview of one skilled in the art to suspend the above described bridging plugs and setting tools by means of drill pipe or tubing, the electrical conductor for controlling the operation of the equipment being lowered through or alongside the pipe; so while several specific embodiments of the invention have been described above in detail, these are intended to be illustrative and not restrictive, and they are susceptible of numerous changes in form and detail within the scope of the following claims.

I claim:

1. A bridging plug for use in bore holes, comprising a support adapted to extend longitudinally in a bore hole, a sleeve of flexible material mounted on the support, upper and lower sleeve retaining members slidably mounted on the support, an upwardly and inwardly tapered member secured to said support at the lower end thereof, a downwardly and inwardly tapered member movably mounted on said support at the upper end thereof, a plurality of slips mounted between said tapered members and said upper and lower sleeve retaining members, respectively, said slips being adapted to slide longitudinally and laterally relatively to the said tapered members, and means for moving said support relatively to said upwardly tapered member.

2. A bridging plug for use in bore holes, comprising a support adapted to extend longitudinally in a bore hole and having a laterally extending stop member formed at the lower extremity thereof, a packing member mounted on the support, upper and lower packing member retainers slidably mounted on the support, a downwardly and inwardly tapered member slidably mounted on said support, a plurality of slips slidably mounted between said tapered member and the laterally extending member on the support, an upwardly and inwardly tapered member slidably keyed to the upper end of said support, a second laterally extending member slidably mounted on said support above said upwardly and inwardly tapered member, a plurality of slips slidably mounted between said second laterally extending member and the upwardly and in-

wardly tapered member, and means for moving said support relatively to said last named laterally extending member.

3. A bridging plug for use in bore holes, comprising a support adapted to extend longitudinally in a bore hole and having a laterally extending stop member formed at the lower extremity thereof, a packing member mounted on the support, upper and lower packing member retainers slidably mounted on the support, a downwardly and inwardly tapered member slidably mounted on said support, a plurality of slips slidably mounted between said tapered member and the laterally extending member on the support, an upwardly and inwardly tapered member slidably mounted to the upper end of said support, a second laterally extending member slidably mounted on said support above said upwardly and inwardly tapered member, a plurality of slips slidably mounted between said second laterally extending member and the upwardly and inwardly tapered member, means for securing said last-named slips temporarily to said upwardly and inwardly tapered member, and means for moving said support relatively to said second laterally extending member.

4. A bridging plug for use in bore holes, comprising a support adapted to extend longitudinally in a bore hole and having a laterally extending stop member formed at the lower extremity thereof, a packing member mounted on the support, upper and lower packing member retainers slidably mounted on the support, a downwardly and inwardly tapered member slidably mounted on said support, a plurality of slips slidably mounted between said tapered member and the laterally extending member on the support, an upwardly and inwardly tapered member slidably mounted to the upper end of said support, a second laterally extending member slidably mounted on said support above said upwardly and inwardly tapered member, a plurality of slips slidably mounted between said second laterally extending member and the upwardly and inwardly tapered member, means for securing said last-named slips temporarily to said upwardly and inwardly tapered member, means for moving said support relatively to said second laterally extending member, and means for preventing movement of said support in one direction relatively to said second laterally extending member.

5. In apparatus for plugging a bore hole, the combination of a support adapted to extend longitudinally in a bore hole, said support having a threaded portion at the upper end thereof, an upwardly and inwardly tapered member secured at the lower end of said support, a packing member slidably mounted on said support above said tapered member, resilient means urging said tapered member away from said packing member, slip means mounted between the lower end of said packing member and said tapered member, and adapted to slide on said tapered member, a downwardly and inwardly tapered member slidably mounted on said support above said packing member, resilient means urging said downwardly and inwardly tapered member away from said packing member, second slip means mounted between the upper end of said packing member and said downwardly and inwardly tapered member and adapted to slide on said downwardly and inwardly tapered member, a nut threaded on said threaded portion of the support above said downwardly and inwardly tapered member, a reversible

electric motor for turning the nut on said support, unidirectional clutch means disposed between said motor and nut, a source of electrical energy at the surface of the earth, electric circuit means connecting said source and motor, and switching means associated with said circuit means for controlling the direction of rotation of said motor.

6. In apparatus for plugging a bore hole, the combination of a support adapted to extend longitudinally in a bore hole, said support having a threaded portion at the upper end thereof, laterally extending stop means secured at the lower end of said support, a packing member slidably keyed to said support, said packing member having downwardly and inwardly and upwardly and inwardly tapered members at the lower and upper ends, respectively, slip means mounted between said stop means on the support and said downwardly and inwardly tapered member and adapted to slide on said downwardly and inwardly tapered member, a laterally extending member slidably mounted on said support above said packing member, second slip means mounted between said laterally extending member and said upwardly and inwardly tapered member and adapted to slide on said upwardly and inwardly tapered member, a nut threaded on said threaded portion of the support above said laterally extending member, an electric motor for turning said nut on the support, unidirectional clutch means between said motor and nut, a source of electrical energy at the surface of the earth, electric circuit means connecting said source and motor, and switching means associated with said circuit means for controlling the direction of rotation of said motor.

7. In apparatus for plugging a bore hole, the combination of a support adapted to extend longitudinally in a bore hole, said support having a threaded portion at the upper end thereof, laterally extending stop means secured at the lower end of said support, a packing member slidably mounted on said support, said packing member having downwardly and inwardly and upwardly and inwardly tapered members at the lower and upper ends, respectively, slip means mounted between said stop means on the support and said downwardly and inwardly tapered member and adapted to slide on said downwardly and inwardly tapered member, a laterally extending member slidably mounted on said support above said packing member, second slip means mounted between said laterally extending member and said upwardly and inwardly tapered member and adapted to slide on said upwardly and inwardly tapered member, shearable means for temporarily securing said second slip means to said upwardly and inwardly tapered member, pawl and rack means for preventing relative movement in one direction between said support and upwardly and inwardly tapered member, a nut threaded on said threaded portion of the support above said laterally extending member, an electric motor for turning said nut on the support, unidirectional clutch means between said motor and nut, a source of electrical energy at the surface of the earth, electric circuit means connecting said source and motor, and switching means associated with said circuit means for controlling the direction of rotation of said motor.

8. An apparatus for plugging a bore hole, comprising a support adapted to be disposed longitudinally of a bore hole and having a threaded upper end portion, a radially expandable packing

member mounted on said support, a nut member threaded on said threaded portion and movable toward said packing member for expanding the latter radially, electric power means detachably connected to said support for rotating said nut, and means actuated by said power means for connecting said power means to said support and detaching said power means from said support.

9. An apparatus for plugging a bore hole comprising a support adapted to be disposed longitudinally of a bore hole and having a threaded end portion, radially contractable and expandable packing means mounted on said support, a nut threaded on said threaded end portion and movable axially of said support to expand said packing member, a casing containing a reversible electric motor, threaded means driven by said motor engageable with said threaded portion to detachably connect said casing to said support, and unidirectional clutch means connecting said nut and said threaded means, whereby said packing member can be expanded and said casing and said support disconnected by said motor.

10. In apparatus for plugging a bore hole, the combination of a support adapted to be disposed longitudinally of a bore hole, said support having a threaded portion at the upper end thereof, a radially expandable packing member mounted on the support, a nut threaded on said threaded portion of the support, means actuated by said nut for expanding said packing member, reversible electric power means for turning said nut on the support, a source of electrical energy for said power means, an electric circuit connecting said source to said electric power means, and means for controlling the direction of rotation of said electric power means.

11. In apparatus for plugging a bore hole, the combination of a support adapted to be disposed longitudinally of a bore hole, said support having a threaded portion at the upper end thereof, a packing member mounted on said support, radially movable slip means slidably mounted on said support below the lower end of said packing member, a second radially movable slip means mounted on said support above said packing member, a nut threaded on the threaded portion of said support above said second slip means and movable axially of said support for moving said slip means radially and expanding said packing member, a reversible electric motor for turning and moving said nut axially of said support, unidirectional clutch means disposed between said motor and said nut, a source of electrical energy at the surface of the earth, electric circuit means connecting said source and motor, and switching means associated with said circuit means for controlling the direction of rotation of said motor.

12. In apparatus for plugging a bore hole, the combination of a support adapted to be disposed longitudinally of a bore hole, said support having a threaded portion at the upper end thereof, laterally extending stop means secured at the bottom end of said support, an expandable and contractable packing member slidably mounted on said support, said packing member having downwardly and inwardly and upwardly and inwardly tapered members at its lower and upper ends, respectively, radially movable slip means mounted between said stop means and said downwardly and inwardly tapered member and adapted to slide on said downwardly and inwardly tapered member, a second member slidably mounted on said support above said packing member, radially movable slip means mount-

ed between said second member and said upwardly and inwardly tapered member and adapted to slide on said upwardly and inwardly tapered member, a nut threaded on said threaded portion of the support for moving said second member axially of said casing, an electric motor for turning said nut on the support to move said nut axially of said support and move said slip means radially, unidirectional clutch means connecting said motor and nut, a source of electrical energy at surface of the earth, electric circuit means connecting said source and motor, and switching means associated with said circuit for controlling the direction of rotation of said motor.

13. Apparatus for setting in a bore hole a bridging plug having a rotatable clutch element mounted on a threaded support for expanding a packing member, comprising a housing adapted to be lowered into a bore hole, a member rotatably mounted in said housing and having threads engageable with said threaded support and adapted to extent longitudinally in a bore hole, means mounted on the housing for maintaining the axis of the housing parallel to the axis of the bore hole, a clutch element in said threaded member for cooperation with the rotatable clutch element of said bridging plug, electric power means mounted in the housing for turning said threaded member about its axis, and means for controlling the direction of rotation of said electric power means.

14. Apparatus for setting in a bore hole a bridging plug having a rotatable clutch element mounted on a threaded support for expanding a packing member, comprising a housing adapted to be lowered into a bore hole, means for maintaining the axis of the housing parallel to the axis of the bore hole, a downwardly extending, rotatable member journaled in said housing and having threads engageable with said threaded support, a reversible electric motor in the housing for turning said threaded member about its axis, a clutch element on said threaded member for cooperation with said rotatable clutch element, and switching means for controlling the direction of rotation of said motor.

15. Apparatus for setting in a bore hole a bridging plug having a rotatable clutch element mounted on a threaded support for expanding a packing member, comprising a housing adapted to be lowered into a bore hole, an incompressible fluid in the housing, means for equal-

izing the fluid pressures inside and outside of said housing, a downwardly extending rotatable member journaled in the housing and having threads engageable with said threaded support, a clutch element on said rotatable member co-operable with said rotatable clutch element, a reversible electric motor in the housing for turning said threaded member about its axis, and switching means associated with said circuit means for controlling the direction of rotation of said motor.

16. A bridging plug for use in bore holes comprising a support adapted to extend longitudinally in a bore hole, a radially expansible sleeve of flexible material on the support, upper and lower retaining members for the sleeve, a frusto-conical expanding member secured at the lower end of said support, a second frusto-conical expanding member movably mounted at the upper end of said support for movement axially of said support to compress said sleeve axially and expand it radially, a plurality of slips slidably secured to said frusto-conical members, means including a rotatable member mounted on said support for movement axially of said support in response to relative rotation between said member and said support for moving said support relatively to said second expanding member, and a clutch element on said rotatable member for connecting said member to a source of power and disconnecting said member from said source of power.

17. In apparatus for plugging a bore hole, the combination of a support adapted to extend longitudinally in a bore hole, said support having a threaded portion at the upper end thereof and stop means at its lower end, a radially expansible packing member mounted on said support, slip means slidably mounted on said support between the lower end of said packing member and said stop means, second slip means mounted on said support above said packing member, a nut threaded on the threaded portion of said support above said second slip means, a reversible electric motor for turning said nut on said support, unidirectional clutch means disposed between said motor and said nut, a source of electrical energy at the surface of the earth, electric circuit means connecting said source and motor, and switching means associated with said circuit means for controlling the direction of rotation of said motor.

WENDELL B. STEWARD.
